CLAIM

The ornamental design for a USB memory device, as shown and described.

DESCRIPTION

FIG. 1 is a front view of the USB memory device.

FIG. 2 is a right side view of the USB memory device, the left side being a mirror image thereof.

FIG. 3 is a rear view of the USB memory device.

FIG. 4 is a top view of the USB memory device, the bottom view being a mirror image thereof.

FIG. 5 is a top, front, right side perspective of the USB memory device.

FIG. 6 is a front view of the inner detachable part of the USB memory device.

FIG. 7 is a right side view of the inner detachable part of the USB memory device, the left side being a mirror image thereof.

FIG. 8 is a rear view of the inner detachable part of the USB memory device.

FIG. 9 is a top view of the inner detachable part of the USB memory device, the bottom view being a mirror image thereof; and,

FIG. 10 is a top, front, right side perspective of the USB memory device, with the inner part detached.
